(57) **CLAIM**

The ornamental design for an injector head, as shown and described.

DESCRIPTION

FIG. 1 is a front perspective view of an injector head in an embodiment of the present invention.

FIG. 2 is a rear perspective view of the injector head of the embodiment of the present invention shown in FIG. 1.

FIG. 3 is a right-side view of the injector head of the embodiment of the present invention shown in FIG. 1.

FIG. 4 is a left-side view of the injector head of the embodiment of the present invention shown in FIG. 1.

FIG. 5 is a top view of the injector head of the embodiment of the present invention shown in FIG. 1.

FIG. 6 is a rear view of the injector head of the embodiment of the present invention shown in FIG. 1; and,

FIG. 7 is a front view of the injector head of the embodiment of the present invention shown in FIG. 1.
